Inventor:

John Stevenson

John Stephenson, of New York, N.Y.

DES. 1960

Letters Patent No. 13,1960-Dated June 19th, 1864.

Design for a Railroad Car Step.

The schedule referred to in these Letters Patent and making part of the same.

To all whom it may concern,

Be it known that I, John Stephenson, of the City, County and State of New York, have invented or produced a new and original design for a Railroad Car Step; and I do hereby declare that the following is a full, clear and exact description of the same, reference being had to the accompanying drawings, making a part of this specification, said drawing being a perspective view of my design.

The main portion or tread a of the step has a horizontal position with its front edge a curved slightly downward and its back edge b, curved slightly upward.

The front corners of the step are rounded at c, the back corners being slightly curved forming concaves, as shown at d.

The main portion of the hangers e, e, at each end of the step are vertical and gradually curve at their lower ends where they join the tread a. The front edges g, the hangers being caused to recede from the front edge of the step and cause the hangers to gradually narrow or diminish in width so that their upper ends will be narrower than their lower parts.

The tread a is perforated with holes, arranged in scroll form, as shown in the drawing.

I claim as new and desire to secure by Letters Patent -

The general configuration of the parts herein shown and described to form a new and original design for a Railroad Car Step.

Witness,

J. P. Hall.

John Stephenson

Attest - G. W. Reed.
